UNITED STATES PATENT OFFICE.

JOHN HALLSTEAD, OF NEW YORK, N. Y.

FLYING-MACHINE.

1,364,752.

Specification of Letters Patent.

Patented Jan. 4, 1921.

Application filed January 10, 1920. Serial No. 350,624.

To all whom it may concern:

Be it known that I, JOHN HALLSTEAD, a citizen of the United States, and a resident of the city of New York, borough of the Bronx, in the county of Bronx and State of New York, have invented new and Improved Flying-Machines, of which the following is a full, clear, and exact description.

This invention relates to flying machines 10 of the heavier than air type and in some respects the invention is similar to the conventional or standard aeroplane.

Among the objects of the invention is to 15 provide a flying machine in which are combined in the same member or members the features or functions of the usual propellers and lifting or sustaining planes.

More specifically stated I provide a machine in which the power elements are devices 20 rotatable around a horizontal axis transverse to the line of flight and comprising a plurality of wings which have many of the characteristics of the wings of an aeroplane, but which include a plurality of 25 parallel blades pivoted along one edge and movable with respect to the general plane of the wings.

Another object of the invention is to provide power devices pivoted upon horizontal 30 axes and combining the functions of lifting, propelling, or sustaining or gliding means.

With the foregoing and other objects in view the invention consists in the arrangement and combination of parts hereinafter 35 described and claimed, and while the invention is not restricted to the exact details of construction disclosed or suggested herein, still for the purpose of illustrating a practical embodiment thereof reference is had to 40 the accompanying drawings, in which like reference characters designate the same parts in the several views, and in which

Figure 1 is a side elevation of a diagrammatic representation of one embodiment of 45 this invention.

Fig. 2 is a vertical longitudinal section through one of the power devices, other parts being broken away.

Fig. 3 is a plan view showing the principal parts of my improvement, parts being 50 broken away to conserve space.

Referring now more specifically to the drawings I show my improvement as applied to a flying machine having a body 10 which in all general respects is or may be substantially the same as the body of an

ordinary aeroplane having cock pit 11 and any suitable rudder or tail mechanism 12 controllable from the cock pit, but with which features *per se* I am not particularly concerned.

Located within the body or at any desired elevation with respect thereto is an engine 13 having a shaft 14 extending laterally from both sides of the body.

Fixed in any suitable manner in a vertical plane on each side of the body is a stationary disk 15 having in its periphery an annular groove 16 adjacent to which are journaled an annular series of anti-friction rollers 17. 70 Fitted upon the disk and adapted to rotate in said groove and anti-frictionally upon the rollers is what I term a compensator comprising an annulus 18 and a series of radially disposed arms 19 of equal length.

Of the wings above referred to I show for each power member four wings each indicated at 19 and comprising two parallel end bars 20 having the general form of the chord of an ordinary aeroplane and fixed 80 upon a pivot bar 21 extending the full length of the wing. Between the bars 20 extend a series of parallel rods 22 upon each of which except the rearmost, is pivotally mounted or swung an imperforate blade 23 85 of any suitable light strong material. The last rod 22 constitutes a stop for the rearmost blade 23 limiting its upward movement and so each of the other rods except the foremost one acts as a stop for the blade ahead 90 of it. The forward or downward swing of the blades is limited by any suitable flexible connections 24. As will be understood from Fig. 2 these blades 23 are adapted to lie approximately in the same plane as the frame 95 of the wing or to be swung downward and forward around their several pivots to a position approaching a right angle or in the position most favorable for beating rearward upon the air for forward propulsion 100 of the machine as shown at A, or to slip freely upward toward the position B. In stage C the wing acts as a sustaining or gliding member and from such position to the position D it acts to beat downward upon 105 the air for a lifting function.

Secured to the engine shaft 14 between the compensator and the inner end of each power member is a spider 25 comprising four radial arms 26 of the same effective 110 length from the center of the shaft as the effective length of the arms 19 from the cen-

ter of the compensator. The engine shaft however is eccentric to the disk and compensator, or in other words the compensator is arranged to rotate readily and freely 5 around one center or axis, while the spiders rotate around a different axis.

Secured rigidly to each wing is a crank 27 one end of which is coaxial with the pivot bar 21 and the other end of which is pivoted 10 at 28 at the outer end of a compensator arm 19. A spider arm 26 is pivoted freely upon the pivot bar 21 at 29 adjacent to the crank 27. The effective length of the crank between centers of the pivots 21 and 28 is 15 equal to the distance between the axes of the shaft 14 and compensator. Thus the arms 19 and 26 form two sides of a parallelogram, while the crank and distance between the centers just referred to constitute 20 the other two sides of the same parallelogram. By virtue of this design of the machine the wings are always carried at the same angle of incidence, such angle being approximately the same as that of an ordinary 25 aeroplane wing, although I wish it to be distinctly understood that I am not to be limited to any particular angle of incidence.

With the rotation of the engine shaft 14 30 the spiders will be rotated accordingly and such rotation of the spiders around the axis of the engine shaft will cause the wings and compensators on opposite sides of the body to similarly rotate around the axis 35 of the compensators, the wings always remaining parallel or to maintain the same angle of incidence. The operation of the power devices will be appreciated from the drawings in view of the following brief 40 summary: While the wings are caused to swing or revolve around the axis of the engine shaft the blades 23 thereof may be said to assume four different stages indicated at A, B, C and D. At stage A the wing is being 45 propelled rearward assuming that the direction of rotation of the engine shaft is as indicated by the arrows on Figs. 1 and 2. At this time the blades 23 are projected downward so as to produce a rearward 50 thrust on the air or a resulting forward thrust on the machine. From stage A to stage B the blades remain open and ascend

in idle position having no propulsive function, nor with a tendency to resist the free movement of the power device. From stage 55 B to stage C there is a transition from the open position of the blades to the closed position in which the blades constitute in effect a structure similar to an ordinary sustaining or gliding aeroplane wing, the 60 blades overlapping one another and making an airtight structure. In this position of stage C the wings have every function of the standard aeroplane wing. From stage 65 C to stage D each wing has a lifting effect 70 beating downward upon the air with a resulting reaction of the machine upward. From stage D to stage A there is a transition again to the open position of the blades for the rearward beating effect. By means of 75 the mechanism set forth herein I contemplate a mechanical device for navigating the air at any desired speed and with respect to vertical or forward directions. In other words while I believe this machine 75 has the possibilities for favorable or superior comparison with standard aeroplanes, it is adapted to rise and alight in practically vertical lines. From the construction shown it will be appreciated that 80 the angle of incidence of the wings will be determined by the angle of inclination of the axis of the power devices with respect to the axis of the annulus 18.

I claim:

The herein described power device for flying machines comprising a power shaft, a spider connected thereto and comprising a series of radial arms, a plurality of parallel wings pivotally connected to the spider 90 arms whereby the wings are caused to revolve around the axis of the shaft, a crank rigidly connected to each wing and extending from the axis of the pivotal connection between the wing and its spider arm, a disk 95 through which the power shaft extends eccentrically and having an annular peripheral groove, and a compensator journaled for rotation upon and around said disk and including a series of radial arms pivotally connected to the ends of the cranks remote from the wing pivots.

JOHN HALLSTEAD.
